UNITED STATES PATENT OFFICE.

FRITZ HÜTTNER, OF BERLIN, GERMANY, ASSIGNOR TO GENERAL ELECTRIC COMPANY,
A CORPORATION OF NEW YORK.

STARTING MECHANISM FOR INTERNAL-COMBUSTION ENGINES.

Application filed May 13, 1922. Serial No. 560,830.

To all whom it may concern:

Be it known that I, FRITZ HÜTTNER, a citizen of the German Realm, residing at Berlin, Germany, have invented certain new and useful Improvements in Starting Mechanism for Internal-Combustion Engines, of which the following is a specification.

This invention relates to two cycle internal combustion engines, and especially those of the high compression type in which the products of combustion are swept out of the cylinder by a blast of scavenging air, the air remaining in the cylinder being subsequently compressed by the instroke of the piston to such high pressure that its heat ignites a charge of fuel injected into the cylinder. It is customary to start such engines by means of compressed air, changing over to operation on fuel as soon as the final temperature of the air compressed in the cylinder on the compression stroke is sufficiently high to ignite the fuel. This final temperature depends, among other things, upon the initial temperature and pressure of the air at the beginning of the compression stroke. The higher this initial temperature and pressure, the higher, of course, is the final temperature and pressure.

The object of the present invention is to provide an improved arrangement in which the initial temperature and pressure on successive cycles will increase very rapidly so that the desired high temperature and pressure for ignition will be obtained more quickly and surely than heretofore, and which will insure reliable ignition in passing from operation with compressed air to operation with fuel.

For a consideration of what I believe to be novel and my invention, attention is directed to the accompanying description and the claims appended thereto.

In the accompanying drawing, Fig. 1 is an elevation, partly in section, of a single cylinder two cycle engine, embodying my invention; Fig. 2 shows diagrammatically a multi-cylinder two cycle engine, with two pistons in each cylinder working in opposite directions; Fig. 3 shows a section on the line 3—3 of Fig. 2; Fig. 4 is a plan view of the multi-cylinder engine shown in Figs. 2 and 3, and Fig. 5 is a detail sectional view taken on line 5—5, Fig. 2.

In carrying out the invention for a two cycle single cylinder engine, as shown in Fig. 1, I provide in the exhaust pipe 1 a shut-off device, such as the flap valve 2. In the ordinary working of the engine this valve is kept open, as shown in dotted lines, but during the starting period the valve is turned to the full line position so as to shut off communication between the cylinder 3 and the exhaust pipe. The closure is made of a yielding character by means of a spring 4 interposed between the arm 5 of the valve and a head 6 on a rod 7 actuated by a lever 8. The tension of the spring can be regulated by a nut 9.

At starting, the compressed air is supplied preferably in abundance to the cylinder 3 through the air starting valve 10. But, with the valve 2 shut, this air does not expand to the pressure of the external atmosphere when the exhaust ports 11 are opened. Instead, its final pressure is that which results from the expansion in the cylinder 3 and the portions of the exhaust passages between the cylinder and the valve 2. If this pressure happens to be higher than the load imposed on the valve by the spring 4, then the excess pressure will force the valve open and escape until the pressure has fallen to the value of the spring load on the valve. But the initial pressure remaining in the cylinder will be high, so that in the following compression stroke of the piston, there will be a considerably higher final temperature than would be the case if the compression had been begun with a somewhat lower initial pressure, for example, that of the scavenging air. The high temperature of compression which is attained with a few additional starting revolutions immediately causes a reliable ignition of the fuel which is injected through the nozzle 12. As is well-known, the starting air used in starting engines of this type has a pressure substantially higher than the compression pressure. During the down stroke this will expand down to a pressure at least as low as that set by the valve spring 4 and on the up stroke it will be compressed to a pressure approximating the compression pressure. The up stroke is effected by the energy stored during the down stroke in the moving parts, which moving parts may include a fly wheel as indicated at W.

In the engine shown in Fig. 1, the air

which escapes past the valve 2 goes into the exhaust pipe and is lost. However, it is possible to retain it in a special receptacle, such for instance as the scavenging pipe or receiver.

In carrying out the present invention in connection with a multi-cylinder engine one or more of the cylinders are provided with air starting valves, these cylinders 10 acting in a way as a motor for operating the others to which fuel is immediately applied. Each of the cylinders having air starting valves is provided with means for shutting off its exhaust. By this arrangement, instead of replacing or supplementing the contents of the air starting cylinders during the scavenging period proper with scavenging air from the receiver which is connected with the scavenging pump, the excess of 15 starting air escapes through the scavenging ports to the receiver thus assisting the scavenging pump in quickly building up the scavenging air pressure to a value above normal. This means that the air supplied 20 to the cylinders to which fuel is being admitted is at a higher initial pressure than would otherwise be the case so that such cylinders will begin to fire more quickly. At the same time, the initial pressure of the 25 air in the air starting cylinders will be higher so that these cylinders will begin to fire as soon as they are switched over to fuel.

Referring to Figs. 2, 3 and 4, A, B, C and D indicate the cylinders of a four cylinder engine having the usual exhaust pipe 1 and charging chamber 14 which surrounds the cylinders. As is well understood, this charging chamber is supplied with scavenging air by a suitable compressor driven by 30 the engine. Each of the cylinders is provided with a fuel injector 15 and cylinders A and B are provided with air starting valves 16 as shown in Fig. 4, and also with valve means for throttling or closing off their exhaust as shown at 2^a in Figs. 3 and 4.

In starting the multi-cylinder engine the valves 2^a are moved to close or throttle the exhaust of cylinders A and B. The starting air valves 16 are then opened at 35 proper intervals to start these two cylinders as air motors. The interval during which the engine is operated on compressed air to start it is termed the starting period and this is what is meant by the term starting 40 period as used in the claims. At the same time fuel will be admitted in the usual manner to cylinders C and D through their fuel valves 15. It will be understood that all the pistons of the respective cylinders are connected to the main crank shaft and that this 45 shaft operates the usual scavenging air pump indicated diagrammatically at P which supplies air to the charging chamber 14. Since the exhausts of cylinders A and 50 B are closed, the expanded starting air in

cylinders A and B cannot escape through the exhaust ports 11 when the upper pistons uncover them. It may escape, however, through the scavenging ports 13 into the chamber 14 when these ports are uncovered 55 by the lower pistons. This means that instead of the cylinders A and B receiving a fresh charge of air from the chamber 14, that they discharge air under pressure into it, thus assisting the scavenging pump in 60 building up the pressure therein. Furthermore, since the pump is normally designed to supply scavenging air to all the cylinders, but during starting is required to supply it to but two of them, it will build up the pressure much more rapidly as less scavenging air is being used. This means that the air with which the cylinders C and D are charged during starting has a high initial 65 pressure which will become still higher on successive strokes so that ignition will very quickly occur in these two cylinders. Also, the initial pressure in cylinders A and B will be higher than normal so that these cylinders will quickly fire when switched over 70 from starting air to fuel.

With this method of starting, the supply of starting air must be abundant or even superabundant, according to the ratio of the cylinders which are started with air to those which operated with fuel, in order to fill the charging chamber quickly with air of sufficient pressure. Excessive supplies of starting air should be given when the engine is in very cold condition.

Fuel is injected into the cylinders by compressed or blast air as it is commonly called through fuel injectors 15 which may be of any suitable construction.

In accordance with the provisions of the 105 patent statutes, I have described the principle of operation of my invention, together with the apparatus which I now consider to represent the best embodiment thereof, but I desire to have it understood that the 110 apparatus shown is only illustrative, and that the invention can be carried out by other means.

What I claim as new and desire to secure by Letters Patent of the United States, 115 is:

1. The combination with an internal combustion engine in which compressed air is used for starting, of a receiver for scavenging air connected with the cylinder, whereby the starting air can expand into said receiver, and means for shutting off the exhaust pipe during the starting period.

2. The combination with a multi-cylinder internal combustion engine in which compressed air is used in certain of the working cylinders for starting, of means for supplying compressed air for starting to such certain cylinders, means for closing the exhaust pipes of such certain cylinders,

and a receiver for charging air connected with the cylinders, and into which the starting air passes during the starting period.

3. The combination with a multi-cylinder internal combustion engine, of a receiver connected therewith supplying scavenging air to the engine, means for admitting compressed air to the engine for starting it, and means for shutting off the exhaust during the starting period whereby the starting air can expand into the receiver.

4. In an internal combustion engine, the combination of a plurality of cylinders having exhaust and scavenging ports, a receiver communicating with the scavenging ports, fuel admission means, valve means for supplying starting air to some of said cylinders, and valve means for shutting off the exhausts of some of the cylinders during the starting period so as to increase the receiver pressure.

5. In a multi-cylinder high compression internal combustion engine having means for admitting compressed air thereto for starting and a receiver for supplying scavenging air thereto, means for cutting off the exhaust of one or more of said cylinders during starting so as to quickly raise the pressure of the scavenging air in the receiver.

6. In a multi-cylinder high compression internal combustion engine having a receiver for supplying air to the scavenging ports, air starting valves on some of said cylinders through which compressed air may be introduced to start the engine, and valves for cutting off the exhaust from the cylinders having the air starting valves so as to quickly raise the pressure of the scavenging air in the receiver.

In witness whereof, I have hereunto set my hand this 24th day of April, 1922.

FRITZ HÜTTNER.
